COIN CONTROLLED LOCK

George A. Long, Hartford, Conn., assignor to The
Long Security Lock Company, Hartford, Conn.,
a corporation of Connecticut

Application December 16, 1937, Serial No. 180,057

16 Claims. (Cl. 194—84)

My invention relates to that class of locks which require the deposit of a coin or token to obtain entrance to a compartment closed by a door to which the lock is affixed, and an object of my invention, among others, is the production of a lock of this type that shall be particularly effective in ensuring all of the functions required of such a lock; a further object of the invention is to provide means in a lock of this type whereby a second unlocking operation of the lock is prevented until the first complete cycle of operations has been completed; and a further object of the invention is to provide a lock of this type which may be operated by a key independently of the coin controlled mechanism.

One form of a lock embodying my invention and in the construction and use of which the objects herein set out, as well as others, may be attained is illustrated in the accompanying drawings in which—

Figure 1 is a front view of a portion of a door and its frame showing my improved lock applied thereto.

Figure 2 is an edge view of the door showing the lock as applied thereto.

Figure 3 is a top view of a portion of the door and its frame with the lock applied thereto, a partially open position of the door being shown in dotted lines.

Figure 4 is a back view of the lock case with the back plate partially broken away to disclose the mechanism within the case.

Figure 5 is a front view on enlarged scale of the upper part of the lock with mechanism therein shown in dotted lines, such mechanism being in its normal position before the beginning of a cycle of operations for releasing the lock.

Figure 6 is a similar view but with the front plate partially broken away to show the mechanism within the case, the parts being in positions after a coin has been inserted and the outside knob has been turned to position to release the latch to enable the door to be opened.

Figure 7 is a view similar to Fig. 6 but showing the position of the parts of the mechanism after turning pressure on the knob has been released and with the door open to enable an occupant to enter the compartment closed by the door.

Figure 8 is a view similar to Figs. 6 and 7 but showing the position of the parts of the locking mechanism after the door has been closed and the compartment is occupied.

Figure 9 is a view illustrating the position of the parts of the lock mechanism after the door has been reopened for exit of the occupant.

Figure 10 is a detail view of the parts comprising the latch mechanism.

Figure 11 is a bottom view of the structure shown in Fig. 10.

Figure 12 is an isometric perspective view illustrating parts of the coin operated mechanism.

Figure 13 is an isometric perspective view illustrating the action of a coin within the receiver.

Figure 14 is a view in central lengthwise section through the knob spindle and surrounding parts.

Figure 15 is a view of a portion of the parts shown in Fig. 14 but in a plane at right angles thereto.

Figure 16 is a view in section on a plane denoted 15 by the dotted line 16—16 of Fig. 14.

Figure 17 is a view in vertical section on different planes passing through the knob spindles.

Figure 18 is a view in cross section on a plane located just underneath the top wall of the case.

Figure 19 is a view in cross section on a plane located just above the top edge of the coin box.

Figure 20 is a view similar to Fig. 12 but illustrating the operation of the device when a slug with a hole therein is attempted to be used.

Figure 21 is a similar view illustrating the further operation of the slug.

Figure 22 is an isometric perspective view illustrating the lug for directing the coin from the coin slot into the receiver.

While my invention is not limited particularly to a lock employed for any specific purpose, yet, as it is particularly adapted for controlling the lock mechanism of doors for closing compartments provided for public use, such as toilets and

the like, I have illustrated and described my invention herein in connection with such a lock. In the drawings herein the numeral 15 denotes a portion of the door frame or jamb of a door opening, as to a toilet compartment, and 16 denotes a portion of the door that closes such opening.

A keeper plate 17 is secured to the jamb in any suitable manner and affords a support for a keeper 18 having an opening to receive a boss 19 projecting from the front edge of a lock case 20, said keeper also having a keeper recess 21 to receive the outer end of a latch bolt 22 mounted for reciprocating movement within the case.

The case 20 is affixed to the front of the door 16 and has a back plate 23 secured thereto in any suitable manner for closing the chamber therein and a coin slot 24 in the front of the case opens into the interior therein. A guiding lug 23 projects from the inner face of the front of the case and has a ledge 26 as shown in Fig. 22 forming a track

35

40

45

50

55

55

for travel of a coin or token into a dish-shaped coin receiver 27 supported at the end of a coin receiver arm 28 rotatably mounted as hereinafter explained. A knob spindle 29 is rotatably supported at one end in a bracket 30 extending across the case intermediate its front and back walls, a leg 31 of the bracket being secured to a post 32 projecting from the front wall of the case for the support of one end of the bracket 5 and its opposite end 33 being secured within a recess 34 in the boss 19, as shown in Fig. 4 and in dotted lines in Fig. 9.

A connector comprising a sleeve 35 and a head 36 is rotatably mounted in and extends through the front wall of the case, as shown in Figs. 14 and 17, the knob spindle 29 being supported in this connector. A recess in the connector head 36, encloses a spindle head 37 on the spindle 29, said spindle head carrying a locking bolt 38 having one end movable into a locking recess 39 on the inner wall of the connector head 36, as shown in Figs. 14 and 16. The bolt 38 is engaged by an eccentrically mounted pin 14 on the end of a plug 40 of a pin tumbler lock which plug is mounted in the shank of an entrance knob 41. This pin tumbler lock is of old and well known construction and a further and detailed description is therefore omitted herein. A spring pressed detent 42 in the spindle head 37 engages notches in the locking bolt 38 to yieldingly retain said bolt in locking or unlocking positions, the detent yielding, when pressure is applied to the bolt, to enable it to be moved. The shank or hub of the knob 41 is secured to the spindle head 35 30 by means of a screw 13 as shown in Fig. 15.

The locking mechanism just described is to enable the door bearing the lock case 20 to be opened without the use of a coin. To effect this purpose a key, usually in the possession of an attendant, is inserted through the opening in the end of the knob 41 and into the key slot in the plug 40, said key positioning the pin tumblers so that the plug 40 may be turned. This will operate the bolt 38 to remove its end from the recess 39 in the connector head 36 as shown in Figs. 14 and 16. The key now being turned further, or the knob if desired, the spindle 29 is rotated within but independently of the connector 35—36 this being effected by reason of the screw 13 (see Fig. 15) which secures the knob shank to the spindle head 37. This operation of the spindle causes a pin 43 projecting from the spindle into a groove 44 in the wall of a hole in the hub of a dog 45 to engage a shoulder 46 55 near the rear end of the latch bolt 22, all as shown in Fig. 10 of the drawings. Continued turning movement of the key or knob effects disengagement of the latch bolt from the keeper and permits the door to be opened.

The coin receiver 27 hereinbefore referred to has a shoulder forming a track 47 upon which the coin travels from the track or ledge 26 until the coin is located within the receiver. A slot 48 is formed at one edge of the receiver, extending preferably to about the center thereof. A shelf 49 on the arm 28 constitutes a slide for coins from the receiver into a coin box 50 located underneath the outer end of the slide. A latch bolt actuator is pivotally mounted upon 60 the spindle 29, this actuator comprising a hub 51 through which said spindle extends, an actuating finger 52 extending from the hub for movement into the coin receiver 27, this finger being adapted to engage the bottom of the receiver when not restricted. An actuating detent

53 projecting from one side of the hub 51 is positioned to engage the shoulder 46 hereinbefore referred to on the latch bolt 22.

In the operation of that part of the structure just described the outer end of the actuating finger 52 will be in a position adjacent to the edge or rim of the coin receiver 27, but spaced therefrom a distance to admit a coin between the two, the finger being held in this position by the pressure of one end of a double acting 10 spring 54 wound around the post 32, and as shown in Fig. 7 of the drawings, the finger in this position resting against a coin releasing lug 55 on the latch bolt 22. The locking bolt 38 having been engaged, by the use of a key, with the notch 39, this being the normal and coin operating position of the parts, a coin 56 is inserted in the coin slot in the case and rolls along the tracks 26 and 47 into the center of the receiver 27 where it is nested between the receiver 15 and the end of the actuating finger 52, and as shown in Fig. 13 of the drawings. The knob 41 now being turned, rotation is communicated to the connector sleeve 35 which is keyed to the coin receiver arm 28, as shown in dotted lines in Fig. 20 25 14 of the drawings. This rotates the coin receiver 27 and its support 35 and moves the coin in the receiver against the end of the finger 52 and the latter is rotated on its axis, carrying the detent 53 against the shoulder 46 on the latch 30 bolt and moving the latter to disengage it from its keeper and permit the door to be opened, the parts now being in the position shown in Fig. 6 35 of the drawings.

However, before the receiver 27 can be moved, 35 as just described, a receiver stop 57 at one end of a pivotally mounted stop lever 58 must be moved from the path of the receiver 27. This is effected by engagement of the curved outer side of the finger 52 with a cam 59 on the lever 58, 40 as shown in Fig. 6 of the drawings. The lever 58 is biased against the finger 52 by one arm of the double acting spring 54, all as shown in Fig. 6 of the drawings. With the parts in their normal positions just previous to the insertion of a coin movement of the receiver is blocked by the stop 57 in its path but a slight space occurs between a coin in the receiver 27 and the stop 57 such that after insertion of the coin the receiver may be moved sufficiently to enable the cam 59 50 to throw the stop 57 out of its path as above described. The object of the stop 57 is to compel insertion of a coin to operate the lock and to thereby prevent movement of the receiver without the use of a coin, and as by means of an 55 instrument thrust through the coin slot or by turning the knob 41.

After the knob 41 has been turned sufficiently to disengage the latch bolt from its keeper to enable the door to be opened, the grasp of the 60 hand upon said knob being released, the receiver 27 is returned to the position shown in Fig. 7 under the action of a receiver spring 60 aided by the spring 54 acting on the finger 52 and through the coin which is still in place in the receiver. 65 In this movement the finger 52 acting against the coin releasing lug 55 moves the latch bolt to its locking position. In this position the receiver is opposite the coin slot 24 and therefore acts to obstruct the entrance of another coin 70 into the coin slot, the receiver being located in this position by means of stop mechanism as follows. A receiver back stop 61 is formed at one end of a back stop carrier 62 pivoted at 63 75 in the upper part of the case 20 as shown in Figs. 75

6 to 9. A stop lug 64 projects from one edge of the carrier 62 to engage the side of the case and thereby determine the active position of the stop as shown in Fig. 6. In this position the outer 5 convex surface of the receiver 27, or a lug thereon, contacts with the stop 61 and positions the receiver to obstruct the entrance of a coin into the coin slot as hereinbefore mentioned. A spring 65 is secured at one end to a pin projecting from 10 the carrier 62 and at its opposite end to a lug projecting from the wall of the case, the spring being so arranged that as said carrier is swung in opposite directions the spring will pass across the pivot 63 and snap the carrier 62 into one 15 of its opposite positions, depending upon which side of the pivot 63 the spring extends, and in a manner that will be readily understood.

The carrier 62 is operated by an actuating lever 66 pivotally mounted intermediate its ends within 20 the case and having a pin projecting from one end into a slot 67 in the stop carrier 62, the opposite end of the lever being adapted to enter a notch 68 cut into the receiver 27 in the opposite side thereof from the slot 67, as shown in Fig. 12 25 of the drawings. In its normal position of rest the stop carrier 62 is located overlying the receiver, as shown in Figure 9. When, however, the knob 61 is turned to operate the latch bolt 22 and release it from its keeper to enable the door to be 30 opened, as hereinbefore described, the coin located in the receiver 27 closes the notch 68 in said receiver and the coin near its edge engaging the end of the lever 66 located in the path of movement of the coin will operate said lever and swing 35 it into the position shown in Figs. 6 to 8. This places the back stop 61 in position to engage the receiver 27 and retain it in the position shown in Figs. 7 and 8.

When the door is closed, following the operations just set out, the latch bolt 22 engaging with 40 the edge of the keeper, is thrust backwardly into the position shown in Fig. 8. In this movement the coin releasing lug 55 on the bolt engages the actuating finger 52 and swings it backwardly, 45 thereby releasing the coin 56 which drops and slides along the shelf 49 and off its edge into the coin box 58. When the door is fully closed and the latch bolt 22 is in position for movement to engage its keeper the finger 52 will be swung forward under the influence of the spring 54 and engaging the lug 55 on the bolt will move the latter and seat it in the keeper recess, as hereinbefore described, the end of the finger 52 now extending slightly into the receiver 27.

55 A paid entrance having been gained to the compartment guarded by the lock and the door being closed and locked as just described, intrusion will be prevented for the reason that the coin receiver 27 being located in front of the coin slot in the case a coin cannot be inserted and it will therefore be impossible to gain entrance to the compartment by the use of a coin. In order to open the door an exit knob 69 is provided on the inside of the door, this knob having a spindle 70 extending through the door and into the lock case. A dog 71 projects from the spindle into a notch 72 in the bolt 22 near its outer end for engagement with a shoulder 12 at one end of the notch. The knob being turned the dog engaging the shoulder 75 of the notch retracts the latch bolt and releases it from its keeper so that the door may be opened. This backward movement of the latch bolt will incidentally operate some of the mechanism hereinbefore described, but to no avail. A resetting finger 73 for resetting the back stop mechanism

for the receiver projects from the hub of the dog 71 into position for engagement with a resetting pin 74 projecting from the back stop 61, and as shown in Fig. 17 of the drawings. As the knob 69 is turned to release the latch bolt the finger 5 73 presses the pin 74 backward causing movement of the back stop 61 from behind the coin receiver 27 and into a position of rest as shown in Fig. 9. Now, as the door is closed, the keeper being engaged by the beveled end of the latch bolt 10 will force said bolt 22 with its lug 55 backwardly, as before described, moving the finger 52 against tension of its spring, and when the latch bolt reaches a position to register with the receiver the spring acting upon the finger 52 will force 15 said finger against the lug 55 on the bolt thereby moving the latter into its locking position. In the final position of the parts a lug 75 on the arm 28 will be forced by the action of the spring 60 against a stop 76 projecting from the inner wall 20 of the case, the receiver being thus located in its position of rest just out of line with the coin slot 24 and the finger 52 resting against the lug 55 on the latch bolt will provide a space just sufficient 25 for the entry of a coin between the receiver and said finger.

When the receiver is in its position of rest the stop 57 is located opposite the edge of the receiver just at one side of the notch 68, thus dogging movement of the receiver from this position. After, however, the door has been opened and the coin has been released the receiver occupies a position a slight distance forward of that just described. To dog the movement of the receiver 30 forwardly from this position a stop 77 in the 35 form of a shoulder at the end of the lever 58 is provided and this will prevent forward movement of the receiver from the position shown in Fig. 7.

To guard against a sticking of the coin within 40 the receiver 27 an ejector 78 in the form of a prong extending from one side of the latch bolt, as shown in Fig. 10, is employed. Should the coin fail to drop from the receiver upon backward movement of the latch bolt 22 in the closing 45 movement of the door, as hereinbefore described, the parts will return to the position shown in Fig. 7. This, however, will be ineffective to prevent repeated functioning of the device. Therefore the ejector 78 is provided and when the knob 50 69 is operated to release the latch bolt the backward movement of the latter will engage the finger with the coin and force it from the receiver.

It will be noted that there are four stops to 55 position the coin receiver, the stop 76 to prevent backward movement by the spring 60 from its normal position of rest, the back stop 61 to determine its position during a cycle of operations of the lock, the front stop 57 to prevent forward 60 movement of said receiver from its position of rest, and the front stop 77 to prevent its forward movement after a cycle of operations has commenced.

In order to determine the number of times the 65 door is opened by the use of a coin a register 79 is employed located at the top of the casing and observable through a window 80 in the side wall or casing as shown in Fig. 17 of the drawings. This register is of the type commonly in use for 70 registering movements of parts and comprising disks with numbers in sequences of ten located thereon, the disks being operatively connected in a manner well understood and for which reason a detailed description is omitted herein, it 75

being sufficient to state that the disks are operated as by means of a shaft 81 extending through one end of the register case that is supported upon a post 82 comprising a part of and rising from the bracket 30, as shown in Fig. 9 of the drawings. A register operating arm 83 is secured at one end to the shaft 81 and is pivotally connected at its opposite end with a register operating link 84, said link being pivotally attached to one end of the actuating lever 66, as shown in Fig. 9 of the drawings.

From this description it will be seen that each time the lever 66 is operated by forward movement of the receiver 27 with a coin therein, in the operation of opening the door, the register 19 will be operated to denote such movement of parts.

In order to aid the movement of the coins from the shelf 49 into the coin box the latch bolt 22 is cut away on one side forming a downwardly inclined chute 85, see Fig. 9, along which the coins pass in their movement from said shelf.

The coin box is inserted through an opening in the bottom of the case and is held in place by means of a locking bolt 86 operated in any ordinary manner by mechanism within the lock case 87 as by means of a key inserted through an escutcheon 88 in the front of the case 20 in a manner that will be readily understood.

30 A bolt stop 89 is formed on the bracket 30 in the path of movement of the dog 45 secured to the spindle 29, as shown in Fig. 10. This dog engaging the shoulder 46 on the latch bolt limits its movement under the influence of the spring 54 when said dog strikes the bolt stop 89.

In the event that a slug or washer with a hole through the center is attempted to be employed, which devices may be readily obtained, the action is illustrated in Figs. 20 and 21 in which it will be noted that when the slug passes into the receiver it will momentarily be hung upon the end of the finger 52, and this being curved to the proper degree, the slug will immediately pass off from the end of the finger and downwardly along the shelf 49 into the coin box under the action of gravity.

The latch bolt 22 has a stop 90 adapted to engage the edge of an opening 30' through the bracket 30 hereinbefore described, in the form as herein shown this stop being located at the rear end of a rib 91 the forward end of which rib constitutes the shoulder 46. The stop 90 limits rearward movement of the latch bolt and the stop 89 limits its forward movement.

55 In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim:

65 1. A coin controlled lock comprising a case having a coin slot therein, a movably mounted receiver into which a coin passes from said slot, an actuator member mounted for movement independently of said receiver and positioned for contact by the flat face of said coin in said receiver and as a result thereof for consequent operation by said coin, a latch bolt having means engageable by said actuator member for operation thereby, means on said bolt engageable with said actuator member for operating thereof in-

dependently of the receiver to release said coin, and means for operating said receiver.

2. A coin controlled lock comprising a case having a coin slot therein, a movably mounted dish-shaped receiver into which a coin passes from said slot, a movably mounted actuating member positioned for contact by the flat face of said coin in said receiver and as a result thereof for consequent operation by said coin, a latch bolt cooperatively positioned relatively to and having means for operation by said actuating member, a stop on said latch bolt to position said actuating member in spaced relation to said receiver a definite distance therefrom to permit entrance of a coin between the receiver and actuating member, and means for operating said actuating member.

3. A coin controlled lock comprising a case having a coin slot therein, a movably mounted dish-shaped receiver into which a coin passes from said slot, a movably mounted actuating member positioned for contact by the flat face of said coin in said receiver and as a result thereof for consequent operation by said coin, a latch bolt cooperatively positioned relatively to and having means for operation by said actuating member, and a lug on said bolt positioned to space said actuating member a definite distance from said receiver for reception of a coin between the receiver and the actuating member, said lug being also positioned for operation of said actuating member independently of said receiver.

4. A lock mechanism comprising a case, a bracket secured within said case and having a transversely extending part with an opening therethrough at one end, a movably mounted operating member, and, a movably mounted actuating member cooperatively positioned relatively to each other and to said bracket and to be operatively connected, a latch bolt mounted for sliding movement on said bracket and projecting at one end through said opening for attachment to said bracket, said bolt being adapted to be operatively connected with said actuating member for operation thereby, a stop at the rear end of said latch bolt to engage the edge of said opening and limit the rearward movement of the latch bolt, and means for operating said members.

5. A lock mechanism comprising a case, a movably mounted operating member and, a movably mounted actuating member cooperatively positioned relatively to each other, a projection on said actuating member, a bracket mounted in said case and having a transversely extending part with an opening therethrough at one end, a latch bolt mounted for sliding movement on said bracket and adapted to be operatively connected with said actuating member for operation thereby, said bolt being retained on said bracket by the edges of said opening, a rib formed on said bolt, a shoulder at one end of said rib being located in the path of movement of said projection for operation thereby and a shoulder at the opposite end of said rib being located for contact with the edge of said opening to limit rearward movement of said bolt, and means for operating said members.

6. A coin controlled lock comprising a case having a coin slot therein, a movable mounted dish-shaped receiver to receive a coin passing from said slot, a movably mounted actuating member of curved horn shape having a blunt pointed end positioned opposite the hollow in said receiver, a latch bolt adapted to be operatively connected with said actuating member for

operation thereby, and means for operating said receiver.

7. A lock comprising a case, a latch bolt movably mounted in said case and projecting therefrom, an actuating spindle, a dog on said spindle operatively connected with said latch bolt, an actuating member for said bolt, an operative connection between said bolt and actuating member, a spindle operating member adapted to be operatively connected with said actuating member, and means for disconnecting said operating member from said spindle for independent operation of said bolt by said dog.

8. A lock comprising a case, a latch bolt movably mounted in said case and projecting therefrom, a knob spindle, a dog on said spindle operatively connected with said latch bolt, an actuating member mounted on said spindle, an operative connection between said bolt and said actuating member, a spindle operating knob adapted to be operatively connected with said actuating member, means for connecting said knob with said spindle for operation of the latter independently of the actuating member, and means for connecting said knob with said actuating member for operation of said bolt thereby.

9. A lock comprising a case, a latch bolt mounted in said case, a knob spindle rotatably mounted in said case, a dog secured to said spindle and operatively connected with said bolt for operating it, an actuating member mounted on said spindle and operatively connected with said bolt for actuating it, a spindle operating knob permanently connected with said spindle, and means for connecting said spindle with and for disconnecting it from said actuating member for operation of said bolt by said dog independently of said actuating member.

10. A lock comprising a case, a latch bolt mounted in said case, a knob spindle rotatably mounted in said case, a dog secured to said spindle and operatively connected with said bolt for operating it, an actuating member mounted on said spindle and operatively connected with said bolt for actuating it, a knob permanently connected with said spindle, and key operated means mounted in said knob and operatively connecting said spindle with and for disconnecting it from said actuating member for operation of said bolt by said dog independently of the operation of said actuating member.

11. A lock comprising a case, a latch bolt mounted in said case, a knob spindle rotatably mounted in said case, a dog secured to said spindle and operatively connected with said latch bolt for operating it, a connector sleeve mounted on said spindle and constituting an actuating member adapted to be operatively connected with and disconnected from said spindle for rotation of the latter independently of the sleeve, a locking bolt carried by said spindle and operating to connect the spindle with said connector sleeve, a knob, and a lock mounted in said knob and operatively connected with said locking bolt for operating it.

12. A coin controlled lock comprising a case having a coin slot therein, a movably mounted

receiver into which a coin passes from said slot, a movably mounted bolt actuator member positioned for contact with and consequent operation by said coin, a latch bolt adapted to be operatively connected with said bolt actuator member for operation thereby, a knob spindle upon which said bolt actuator member is mounted for rotation of the former independently of the latter, a connection between said spindle and bolt for operation of the latter independently of said actuating member, a knob permanently connected with said actuating member, and means for connecting said knob with said actuating member for operation of the latter.

13. A coin controlled lock comprising a case having a coin slot therein, a movably mounted receiver into which a coin passes from said slot, a movably mounted actuating member positioned for contact with and consequent operation by said coin, a latch bolt having means for operation by said actuating member, a movably mounted stop to prevent forward movement of said receiver from its normal position of rest, means for removing said stop from the path of said receiver, and means for operating said receiver.

14. A coin controlled lock comprising a case having a coin slot therein, a movably mounted receiver into which a coin passes from said slot, a movably mounted actuating member positioned for contact with and consequent operation by said coin, a latch bolt having means for operation by said actuating member, a movably mounted stop member having a stop to prevent forward movement of said receiver from its normal position of rest and also having another stop to prevent forward movement of said receiver from an intermediate position, means for removing said stop from the path of movement of said receiver, and means for operating said receiver.

15. A coin controlled lock comprising a case having a coin slot therein, a movably mounted receiver into which a coin passes from said slot, a movably mounted actuating member positioned for contact with and consequent operation by said coin, a latch bolt having means for operation by said actuating member, a back stop movably mounted to position said receiver in the path of movement of a coin into said slot, means for actuating said back stop, a front stop movably mounted to limit forward movement of the receiver from said position, means for operating said front stop, and means for operating said receiver.

16. A coin controlled lock comprising a case having a coin slot therein, a movably mounted receiver into which a coin passes from said slot, a movably mounted actuator member positioned for contact with and consequent operation by said coin, a latch bolt movably mounted in said case, and having means for operation of said actuator member and a movably mounted stop for determining a position of said receiver, said actuator member having means for actuating said latch bolt, and also having means for removing said stop from its stop position.

GEORGE A. LONG.
